UNITED STATES PATENT OFFICE.

ROLLIN L. DRAKE, OF PORT ARTHUR, TEXAS, ASSIGNEE TO THE TEXAS COMPANY, A CORPORATION OF TEXAS.

EXPANDING DEVICE FOR CAN-BUMPING PRESSES.

1,164,582.

Specification of Letters Patent. Patented Dec. 14, 1915.

Application filed October 23, 1913. Serial No. 736,775.

To all whom it may concern:

Be it known that I, ROLLIN L. DRAKE, a citizen of the United States, residing at Port Arthur, in the county of Jefferson and State of Texas, have invented certain new and useful Improvements in Expanding Devices for Can-Bumping Presses, of which the following is a specification.

This invention relates broadly to new and useful improvements in expanding device for can bumping presses.

The bumping press in connection with which the expanding device is shown for the purposes of this application as being used, may be of a well known construction now in common use in the manufacture of tin and sheet metal cans and is used for the purpose of crimping together the seams of the can. This expanding device, is intended to be used on bumping presses in the manufacture of cans having walls at angles to each other joined by one or more seams, and more particularly the ordinary square can, whose body is formed of two sheets of metal having their corresponding edges crimped together, thus forming two opposing seams or joints, and is provided for the purpose of insuring a close well formed seam which will be absolutely liquid proof after it is soldered and consequently not liable to leak, this result being obtained in a manner which will be specifically set forth hereinafter.

With the above and other objects in view, the invention has particular relation to certain novel features of construction, operation and arrangement of parts, an example of which is given in this specification and illustrated in the accompanying drawings, wherein—

Figure 1 is a perspective view of the bumping press with the expanding device embodying my invention attached thereto. Fig. 2 is a perspective view of the expanding device. Fig. 3 is a perspective view of a can in the process of formation and before the ends are secured thereon. Fig. 4 is an edge view of one side of the expanding device, shown in its relation to the horn of the press. Fig. 5 is a side elevation thereof. Fig. 6 is an edge view of one of the expanders. Fig. 7 shows a plan view of the expander support. Fig. 8 is a sectional end view of the device taken on the line *a—a* of Fig. 5. Fig. 9 is a sectional end view of the expander support taken on the line *b—b* of

Fig. 7. Fig. 10 is a plan view of the cam plate. Fig. 11 is a sectional view of the device taken on the line *c—c* of Fig. 1. Fig. 12 is a fragmentary sectional view taken on the line *d—d* of Fig. 1. Fig. 13 is a fragmentary end view partly in section of the hammer, and Fig. 14 is a side elevation of the plunger rod and connections. Fig. 15 is a vertical detail section through the horn.

Referring now more particularly to the drawings wherein like numerals of reference designate similar parts in each of the figures, the numeral 1 refers to the press stand which carries the operative mechanism of the press. The stand 1 carries what is commonly known as the "horn" projecting from the side thereof. This horn includes the member or plate 2 which is fixed to a slide 2' and which projects in a vertical plane from the press stand.

The plate 2 on each side thereof, is provided with laterally extending rods or shafts 3, 3, preferably two in number, and extending into bosses 3^a, 3^a, on said plate and projecting therefrom on opposite sides thereof, said rods being adjustable in said bosses and located in a horizontal plane, said rods being each held in place by a set screw projecting through the boss. These rods extend an equal distance each way from the plate 2, and the free ends thereof are socketed in the expander supports 4, 4, which are preferably in the form of bars extending lengthwise of the said plate and preferably equal in length to the length of the plate. The slide 2' is vertically slidable relative to the stand, moving in the side grooves 1', 1' of the stand 1, as shown in Fig. 12 and the horn carried by said slide thus has a limited slideable, vertical movement on the stand.

The upper and under edges, respectively, of the plate 2 have cylindrical rods 5 and 6, secured thereto whose inner ends are flush with the inner end of the plate and whose outer ends project preferably some distance beyond the outer end of the plate 2, as shown in Figs. 1 and 2. Fixed to the front side of the stand 1 is a seat or anvil 7, of a length preferably equal to the length of the plate 2 and alined thereunder, and the upper side of this seat has a groove 7' extending from end to end thereof.

A vertically slideable hammer 8 is provided which is anchored in the stand just above the horn and this hammer is reciprocated up

and down by the plunger rod 9, the upper end of said rod being pivoted to the offset 10 on the drive crank shaft 11, said crank shaft operating to reciprocate the plunger rod up and down. Rotation is imparted to said shaft through the pulley wheel 12 which receives rotation from a suitable motor, (not shown). As the shaft 11 is rotated, the hammer 8 is reciprocated up and down, with the plunger rod. The hammer 8 is provided on opposite sides with vertical guide ribs 8' arranged to slide in grooves 8" in the press stand.

The underface of the hammer 8 has a seat 13, preferably equal in length to the plate 2 and alined thereabove, and the underface of this seat has a shallow groove extending from end to end thereof. The bars 4 on each side of the plate 2 form supports for the expanders 14, 14. These expanders are oblong members whose free ends project out some distance beyond the outer ends of the bars 4 and their outer faces are oval, as shown at 14^a, in Fig. 8. The inner face of each of the expanders 14, has a lengthwise rib 15, said ribs extending into lengthwise grooves 16, 16, in the outer edges of the bars 4, 4, in which the corresponding ribs 15, 15 rest. The outer side of each of the bars 4 has a plurality of notches 4^a, preferably two, one side of each notch being abrupt as at 4^b and the other side sloping, forming the inclined faces 17, 17, and the expanders 14, 14 having inwardly projecting shoulders 18, 18, which fit into said notches and whose inner ends are inclined as at 18^a, so as to fit against the said inclined faces 17, 17. The inner edges of the expander supports 4, 4 also have notches 4^c opposing the notches of the outer edges thereof and arranged in the reverse position, forming necks 19, 19 through which extend oblong slots 20, 20 and extending through the slots 20, 20 are the bolts 21, 21 whose inner ends are threaded and engage in tapped holes 21^a in the shoulders 18, 18 and secure the ribs 15 against disengagement from the grooves 16 in the supports 4.

Alined with the expanders 14, 14, and secured upon each side of the stand 1 are cam plates 22, 22 each having a slot 23 therein. The lower end of this slot extends vertically, but the upper end is forwardly inclined, forming a cam 24, and the inner end of each expander has an inwardly projecting stud 25 which projects into its corresponding slot 23.

In the process of forming a can, two sheets of metal are bent so that their sides extend at right angles to each other and the edges are suitably crimped and the crimps of the two sheets are then interlocked, as shown in Fig. 3, and placed over the horn 2 so that the crimped edges, or seams, will rest in grooves 5^a, 6^a, above and below the rods 5 and 6, respectively. The press is then opera-

tively connected with its driving means and a downward stroke is thereby imparted to the hammer 8. The hammer is thereby driven downward, the seat 13 imparting a sudden stroke to the under seam which at 70 that moment rests in the said groove of the seat 7 and the crimped edges are thus firmly locked together. However, as the hammer descends, the studs 25 move downwardly in the slots 23 and impart a rearward pull to 75 the expanders 14. As the expanders move back the inclined faces of the inner ends of the shoulders 18, 18 move on the inclined faces 17, 17, causing said expanders to spread relative to each other, the bolts 21, 21 80 moving in their slots 20, 20.

The spreading of the expanders 14, 14 is exerted against the sheets of which the sides of the can are formed and causes the crimped edges to completely engage just before the final stroke of the hammer is imparted and this insures the complete locking of the crimped edges.

Extending upward from the upper edge of the slide 2' are the rods 26, 26 which extend up through orifices 27, 27 in the laterally extending portions of the hammer 8. As the hammer moves up and down it slides on the rods 26, 26. The upper end of each rod 26 has an enlarged head 28 and just before the hammer reaches the limit of its upward movement it engages against the heads 28 and through the rods 26, 26 elevates the horn. At the same time by reason of the forward curve of the upper ends of the slots 23, the expanders 14, 14 are driven forward and pulled in or retracted, the heads of the bolts 21 moving on the inclined faces of the notches in which they rest and causing the expanders to move toward each other and the tension on the can is thereby released so that the can may be readily removed from the horn.

I have shown only one form of this device but it is obvious that mechanical variations may be made therein without departing from the principle of the invention, and I hereby reserve the right to make such changes as will not depart from the scope of the appended claims.

What I claim and desire to secure by Letters Patent of the United States is

1. In a bumping press, a stand, a reciprocable horn on said stand, an anvil in the path of movement of said horn, a hammer to engage the horn to move it toward the anvil, an expander carried by the horn, and means to expand said expander during movement of the said horn toward the anvil.

2. In a bumping press, a stand, a member vertically movable thereon, an anvil beneath said member, a hammer to engage the upper portion of said member to move it toward the anvil, expanders carried by said member, and means whereby movement of said

member toward the anvil expands said expanders.

3. In a bumping press, a stand, a member vertically movable thereon, an anvil beneath said member, a hammer to engage the upper portion of said member to move it toward the anvil, an expander carried by said member, and means whereby movement of said member toward the anvil expands said expander.

4. In a bumping press, a stand, a member vertically movable thereon, an anvil beneath said member a hammer to engage the upper portion of said member to move it toward the anvil, an expander carried by said member, and cam means whereby movement of said member toward the anvil expands said expander.

5. In a bumping press, a stand, a member vertically movable thereon, an anvil beneath said member, a hammer to engage the upper portion of said member to move it toward the anvil, an expander carried by said member, cam means whereby movement of said member toward the anvil expands said expander, and means to retract said expander upon movement of the member away from the anvil.

6. In a bumping press, a stand, a reciprocable horn on the stand, an anvil in the path of movement of the horn, a hammer to engage the horn to move it toward the anvil, expanders mounted on opposite sides of said horn, and movable lengthwise thereof, means between said expanders whereby lengthwise movement of the expanders projects and retracts the same, and means for moving said expanders lengthwise upon movement of the horn toward and away from the anvil.

40 7. In a bumping press, a stand, a reciprocable horn on the stand, an anvil in the path of movement of the horn, a hammer to engage the horn to move it toward the anvil, expanders mounted on opposite sides of said horn, and movable lengthwise thereof, means between said expanders whereby lengthwise movement of the expanders projects and retracts the same, and a cam for moving said expanders lengthwise upon movement of the horn toward and away from the anvil.

8. In a bumping press, a stand, a reciprocable horn on the stand, an anvil in the path of movement of the horn, a hammer to engage the horn to move it toward the anvil, expanders mounted on opposite sides of said horn and supported thereby, inclined surfaces between the expanders and the horn whereby movement of the expanders in one direction project the same and in the other direction, retracts them, and means whereby the reciprocating movements of the horn move the expanders.

9. In a bumping press, a stand, a reciprocable horn on said stand, an anvil in the path of movement of said horn, a hammer to en-

gage the horn, an expander, and means acting automatically upon movement of the horn in one direction to project the expander and in the other direction to retract the same.

10. In a bumping press, a stand, a reciprocable horn on the stand, an anvil in the path of movement of said horn, a hammer to engage the horn to move it toward the anvil, means connecting the hammer and horn to retract the latter from the anvil, an expander, and means acting automatically by movement of the horn in one direction to project the expander and in the other direction to retract the same.

11. In a bumping press, a supporting stand, a horn projecting therefrom and slideable relative thereto, reciprocable expanders carried by the horn and laterally movable relative thereto, and means whereby the sliding movement of the horn operates the expanders.

12. In a bumping press, a stand, a horn slidably connected thereto, a seat fixed to the stand and arranged on one side of the horn, a slideable hammer arranged on the side of the horn opposing said seat, means operatively connected with the hammer for reciprocating the same, reciprocable expanding members, one arranged upon each side of said horn and reciprocable laterally relative thereto, and means whereby the sliding movement of the horn operates the expanding members.

13. In a bumping press, a stand, a vertically movable horn slidably connected to the stand, a seat fixed to the stand underneath the horn, a reciprocating hammer slidably connected to the stand and arranged above the horn, means operatively connected with the hammer and reciprocating the same, expanding members carried by the horn, one arranged on each side, the inner ends of said members having connection with the stand and arranged to expand as the horn moves downward.

14. In a bumping press, a supporting stand, a horn projecting therefrom and having a slideable connection therewith, a seat fixed to the stand underneath the horn, a reciprocating hammer arranged on the opposite side of the horn to said seat, means operatively connected with the hammer and reciprocating the same, expanding members one arranged upon each side of said horn, cams carried by the stand, one on each side, operative connections between the cams and the respective expanding members and arranged to impart longitudinal movement to said expanding members in unison with the movement of the horn, and means whereby said longitudinal movement causes the expanding members to be reciprocated relative to the horn.

15. In a bumping press, a supporting stand, a member projecting therefrom and

having vertical movement relative thereto, a seat fixed to the stand underneath said projecting member, a reciprocating hammer arranged above said member, means operatively connected with the hammer and reciprocating the same, expanders, one arranged upon each side of said member, contacting inclined faces carried by said member and said expanders, respectively, cams 10 carried by the stand, one on each side, operative connections between the cams and the respective expanders and arranged to impart relative movement to said contacting inclined faces as the said member moves vertically.

15 16. In a bumping press, a supporting stand, a member projecting therefrom and having a vertical movement relative thereto, expanders, one arranged upon each side of said member, contacting inclined faces carried by said member and said expanders, respectively, cams carried by the stand, one on each side, operative connections between the cams and the respective expanders and so arranged as to impart relative movement 20 to said contacting inclined faces as the said member moves vertically.

25 17. In a bumping press, a supporting stand, a member projecting therefrom and

having a vertical movement relative thereto, an expander, contacting inclined faces carried by said member and said expander respectively, a cam carried by the stand, an operative connection between the cam and the expander and so arranged as to impart relative movement to said contacting inclined faces as the said member moves vertically.

18. In a bumping press, a stand, a reciprocal horn on the stand, an anvil in the path of movement of said horn, a hammer to engage the horn to move it toward the anvil, an expander carried by the horn, said expander being mounted for movement lengthwise of the horn and laterally thereof, means whereby said longitudinal movement of the expander causes said lateral movement thereof, and means operable during movement of said horn toward the anvil to cause said longitudinal movement.

In testimony whereof I have signed my name to this specification in the presence of two subscribing witnesses:

ROLLIN L. DRAKE.
